US0D1110304S

(12) **United States Design Patent** (10) **Patent No.:** **US D1,110,304 S**
(45) **Date of Patent:** **** Jan. 27, 2026**

(54) **PAIR OF EARPHONES**

(71) Applicant: **Apple Inc.**, Cupertino, CA (US)

(72) Inventors: **Vijay Karthik Koneru**, Los Angeles, CA (US); **Robert Boyd**, Los Angeles, CA (US); **Duy P. Le**, Los Angeles, CA (US); **Joseph F. Dembs**, Los Angeles, CA (US); **Jeffrey Scott Croyle**, San Francisco, CA (US); **Matthew Phillip Casebolt**, Fremont, CA (US); **Matthew Vincent Costello**, Soquel, CA (US); **Elvin Chu**, San Francisco, CA (US); **Guillaume Raoult**, San Francisco, CA (US); **Zu-Ning Chen**, San Francisco, CA (US); **Christopher Kuh**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/882,283**

(22) Filed: **Jan. 12, 2023**

Related U.S. Application Data

(63) Continuation of application No. 29/784,431, filed on May 19, 2021, now Pat. No. Des. 975,683.

CLAIM

The ornamental design for a pair of earphones as shown and described.

DESCRIPTION

FIG. 1 is a top perspective view of a pair of earphones showing the claimed design;

FIG. 2 is a bottom perspective view thereof;

FIG. 3 is a front view thereof;

FIG. 4 is a rear view thereof;

FIG. 5 is a side view thereof;

FIG. 6 is an opposing side view thereof;

FIG. 7 is a top view thereof; and,

FIG. 8 is a bottom view thereof.

The broken lines in the figures show portions of the pair of earphones that form no part of the claimed design.

The innermost circular features inside of the earphone tips shown in FIGS. 1 and 5 form no part of the claimed design.

1 Claim, 8 Drawing Sheets
